UNITED STATES PATENT OFFICE.

NICOLA STRAMAGLIA, OF CHICAGO, ILLINOIS.

SPOTLIGHT AND OPERATING MECHANISM.

Application filed October 1, 1921. Serial No. 504,818.

To all whom it may concern:

Be it known that I, NICOLA STRAMAGLIA, a citizen of the United States, residing at Chicago, in the county of Cook and State 5 of Illinois, have invented new and useful Improvements in Spotlights and Operating Mechanism, of which the following is a specification.

This invention relates to an improved spot 10 light and operating mechanism therefor, and has for its primary object the construction and association of parts whereby the spot light may be used to greater advantage.

An object of the invention is the novel 15 manner of constructing the mechanism so that the light may be given horizontal and vertical movement for properly directing the rays of light.

Another object of the invention is to give 20 the various movements to a spot light and lock the same in any position.

Besides the above my invention is distinguished in the improved form of spot light 25 so that the illuminating means thereof may be readily removed for positioning upon various metallic structures.

With these and other objects in view the invention will be better understood from the 30 following detailed description and the accompanying drawings wherein:

Fig. 1 is a side elevation of my invention.

Fig. 2 is a detail view of a part of the spot 35 light removed and utilized for another purpose.

Fig. 3 is a longitudinal sectional view.

Fig. 4 is a sectional view on the line 4—4 of Fig. 3.

Fig. 5 is a sectional view on the line 5—5 of Fig. 3.

Fig. 6 is a sectional view on the line 6—6 of Fig. 3.

Fig. 7 is a diagrammatic view of the wiring.

Again referring to the drawing illustrating one of the many constructions of my invention the numeral 1 designates my improved spot light consisting of a casing 2 of the required shape and having hinged to its front edge the clamping ring 3. This 45 clamping ring is constructed to clamp in place the flange 4 on the reflector 5 of the illuminating means. This reflector includes a socket 6 for supporting the bulb 7 and connected to and forming the base for the reflector is an electric magnet 8. Secured to the surface of the reflector are binding

posts 9 for making the proper connection while at all times allowing for disconnection of the reflector from the casing. By referring to Fig. 2 of the drawings it will be seen that the light may be readily removed and supported upon any metallic structure such as the frame of an automobile as the magnetism of the magnet will properly act to support the reflector. Referring to the diagrammatic view illustrated in Fig. 7 of the drawings it will be seen that the bulb 7 is arranged in a circuit 10 which includes a battery 11 and a switch 12. The magnet 8 is arranged in partial circuit 13 braced across the battery and including a switch 14. Thus it will be seen that the bulb may be illuminated without energizing the magnet 8 or the magnet 8 may be energized without illuminating the bulb 7; by closing both the switches 12 and 14 both the bulb and magnet can be rendered active.

The operating mechanism for my improved light consists of a post 15 which rotatably supports the auxiliary hollow shaft 16, one end of this shaft is provided with ratchet teeth 17 while the other end is rigidly connected to an arm 18 and a bracket 19. The arm 18 has connection with the casing 2 as indicated at 20 while the bracket 19 rotatably supports the stub shaft 21 that in turn is rigidly connected to the casing 2.

Rotatably supported within the auxiliary hollow shaft 16 is a main hollow shaft 22 which has secured to one end the bevel gear 23 meshing with the second bevel gear 24 that is connected to the shaft 21. The remaining end of the shaft 22 has connected thereto a collar 25 rotatably associated with any suitable frame or stationary switch 26 that will be connected to the main current conducting wires. In this particular instance I have switch 26 closed by inserting the plug 27.

As far as I have proceeded it will be seen that by turning one of the shafts the lamp will be given horizontal movement and by operating the other shaft the lamp will be given vertical movement, thereby enabling the operator to properly direct the rays of light. A main hand wheel 28 is keyed to the main shaft for sliding movement and is provided with teeth 29 normally forced into engagement with the teeth 17 by the spring 30. An auxiliary hand wheel 31 is provided with teeth 32 normally forced into engagement with the teeth 33 on the post 15 by a

spring 34. This hand wheel 31 is keyed to the shaft 16 for sliding movement.

From the foregoing description taken in connection with the accompanying drawings it will be apparent that by sliding the hand wheel 28 the same will be disengaged from the teeth 17 so that by turning the hand wheel the shaft 22 will be operated for giving horizontal movement to the light; as soon as pressure is relieved from the hand wheel 28 the spring 30 will force the teeth into locking engagement for holding the light in adjusted position. By giving the same action to the hand wheel 31 the shaft 16 can be operated for giving vertical movement to the light.

It is, of course, to be understood that the invention may be constructed in various other manners and the parts associated in different relations and, therefore, I do not desire to be limited in any manner except as set forth in the claims hereunto appended.

Having thus described my invention what

I claim is:-

1. In combination, a light, a bracket supporting the light for horizontal and vertical movement, a main shaft having a gear connection with the light to move it horizontally, a hollow auxiliary shaft encircling said main shaft and connected to the bracket for swinging the light vertically, a hand wheel on said auxiliary shaft, a second hand wheel slidably supported upon and adapted to turn said main shaft, said second hand wheel having a locking engagement with said auxiliary shaft when in normal position.

2. In combination, a light, a bracket supporting the light for horizontal and vertical movement, a main shaft having a gear connection with the light to move it horizontally, a hollow auxiliary shaft encircling said main shaft and connected to the bracket for swinging the light vertically, a hand wheel on said auxiliary shaft, a second hand wheel slidably supported upon and adapted to turn said main shaft, said second hand wheel having a locking engagement with said auxiliary shaft when in normal position, and an elec-

tric current controlling switch carried by one end of said main shaft.

3. In combination a light, a bracket supporting the light for horizontal and vertical movement, a main shaft having a gear connection with the light to move the same horizontally, a hollow auxiliary shaft connected to the bracket for swinging the light vertically, a hand wheel having slidable connection with the auxiliary shaft for turning the same and adapted, when in one position, to be locked against movement, a second handwheel slidably supported upon and adapted to turn the main shaft, said second hand wheel having a locking engagement with the auxiliary shaft when in normal position.

4. Operating mechanism for light comprising a main shaft, an auxiliary shaft encircling the main shaft, a post supporting the auxiliary shaft for movement, a hand wheel keyed to the auxiliary shaft for sliding movement thereon and provided with teeth adapted to have locking engagement with the post, a spring for forcing the hand wheel into locking engagement with the post, and a second hand wheel having a keyed slid- 70 able connection with the main shaft and normally, yieldably, forced into locking engagement with said auxiliary shaft.

5. Operating mechanism for light comprising a main shaft, an auxiliary shaft encircling the main shaft, a post supporting the auxiliary shaft for movement, a hand wheel keyed to the auxiliary shaft for sliding movement thereon and provided with teeth adapted to have locking engagement with the post, a spring for forcing the hand wheel into locking engagement with the post, and a second hand wheel having a keyed slid- 85 able connection with the main shaft and normally, yieldably forced into locking engagement with said auxiliary shaft, a switch device associated with the end of said main shaft.

In testimony whereof I affix my signature.

NICOLA STRAMAGLIA.
